GEOMETRICAL INSTRUMENT

Paul G. Jennings, Denver, Colo., assignor to Remington Arms Company, Inc., Bridgeport, Conn., a corporation of Delaware

Application March 6, 1943, Serial No. 478,171

9 Claims. (Cl. 33—174)

This invention relates, in general, to a gauge, and, in particular, to a gauge for measuring profiles.

In the manufacture of certain types of tools, as, for instance, metal punches such as used in drawing metallic tubular articles, the article engaging portion of the tool must be shaped with extreme accuracy to specific dimensions, the permissible variations or tolerances being no more and sometimes less than one one-thousandth of an inch.

Various methods are used for shaping the tools to specifications, the two most common being by grinding or by progressive turning operations. The latter term will be understood to designate the method of successively cutting progressively increasing or decreasing diameters at equal increments along the length of the tool blank. A diagrammatic illustration of a fragmentary portion of a tool profiled in the above described manner is shown in Fig. 9 of the drawings.

It will be seen that during the initial stages of manufacture, the profile of the tool from its pointed end to its shank comprises a plurality of shoulders *s* of progressively increasing diameter, each diameter having a specific dimension and spaced equally at every five hundredths inches along the axis of the tool blank. After cutting the profile shoulders, a file or other suitable abrading means is drawn over the shoulders of the tool blank while it is being rotated to remove the sharp edges and form the smooth continuous curve or profile *P*. The profile may then be finished with a high polish or a chromium plate in accordance with well known methods.

The importance of extremely accurate profile dimensions will be obvious to those skilled in the art, but for the purpose of emphasis, it may be pointed out that a punch such as the one described above and which exemplifies the type of punch used in forming the bullet jacket of a .50 caliber armor piercing projectile is carried in a reciprocating head which drives the punch down with considerable force into engagement with a partially formed bullet jacket supported in a jacket die.

Clearly, any slight inaccuracies in the dimensions of the die or in the profile of the punch will manifest themselves as a wrinkle, groove, thin spot or other deformation or imperfection in the wall of the bullet jacket. Moreover, when the punch is withdrawn from the die, it will not free itself readily from the imperfect jacket, but tends to carry the jacket upwardly out of the die, in which event, the jacket and the punch itself will be deformed or broken on the subsequent down-

ward stroke of the punch. The only practical way of avoiding such malfunction is to detect any inaccuracies in the profile of the punch prior to its use by making precise measurements of substantially the entire profile of the finished punch.

It is an object of the present invention to provide an improved gauge means for measuring the profiles of tools. A further object is to provide an improved gauge for conveniently and accurately measuring progressively increasing or decreasing transverse dimensions of a tool at successive increments along the longitudinal dimension of the tool.

Other objects, features and advantages of the invention will be described in detail in the following specification.

The gauging device shown and described herein is but one exemplary embodiment of applicant's invention and one adapted particularly for measuring the profiles of metal draw tools such as used in the manufacture of ammunition components. It will be understood, however, that the device may have other uses and that the invention embodies all modifications thereof within the scope of the appended claims.

In the drawings:

Fig. 1 is a perspective view of the gauge unit of this invention separated for the purpose of clarity into two units A and B.

Fig. 2 is an end elevation partially in section of unit A showing unit B assembled thereon.

Fig. 3 is a side elevation of the assembled gauge shown in Fig. 2.

Fig. 4 is a side elevation, partially broken away, of unit A.

Fig. 5 is an end elevation of unit A on line 5—5 of Fig. 2.

Fig. 6 is an end elevation of unit A on line 6—6 of Fig. 4.

Fig. 7 is a plan view of the assembled carriages of the gauge.

Fig. 8 is a perspective view of the joining means for securing the second rail to the first carriage.

Fig. 9 is a diagrammatic view of a tool having a progressively turned profile.

Referring to the drawings, Fig. 1 shows a perspective view of the improved profile gauge of this invention in use as a lathe attachment. For the sake of clarity, the gauge is shown as separated into two units A and B adapted to be joined together, as shown in Figs. 3, 5 and 7, by suitable fastening means hereinafter described. A lathe bed is indicated at 15 and is provided with a common type of tool holder or carrier 16 slidable on ways 17 of the lathe bed. The as-

sembled profile gauge, indicated generally at 18 in Fig. 2, is removably secured to the tool carrier 16 by clamping means comprising a bolt 19 provided with a relatively thin rectangular head 20 having dimensions proportional to the dimensions of the way 22 of the tool carrier so as to make a freely sliding fit therein. The shank 23 of the bolt projects upwardly substantially vertically through an apertured gauge block 24 hereinafter described and the longitudinal slot 25 of a frame member 26. The upper end of the bolt is adapted to threadedly engage in the vertical bore of a hub-shaped clamping nut 21 which is mounted on top of the frame member 26 spanning the slot 25 and is provided with a rim having radially drilled holes 28 to slidably accommodate a handle or operating rod 29.

The longitudinal slot 25 of the frame member enables displacement of the gauge laterally with respect to the longitudinal axis of the lathe chuck 30. In order to properly position the gauge vertically with respect to the longitudinal axis of a tool or workpiece T held in the chuck, a suitable number of gauge blocks 24 may be provided of different thicknesses, each being apertured to slide down over the bolt 19 onto the upper surface of the tool carrier. In its assembled position on the tool carrier, the frame member 26 is mounted on top of the gauge block 24 and is securely fastened to the tool carrier by turning the operating handle 29 clockwise as seen in Fig. 1.

The laterally extending end of the frame member 26 supports an L-shaped member 33 which is secured at its upper end by bolts 34 to the end 32 of the frame member. Although the frame member and L-shaped member are shown as comprising two separate pieces joined by fastening means, it will be understood that these two members may be welded together or formed from a single piece.

Secured fast at the lower end of the L-shaped member by suitable bolts 35 is a substantially horizontal rail member 36 which, as shown in Figs. 1, 2 and 3, comprises a longitudinal rib 37 extending along the upper edge of the rail member and guide means 38 intermediate the ends thereof.

The guide means 38 comprises an upstanding tongue substantially equal in thickness to the rib 37 and rectangular in shape except for an arcuate front edge 39. Bolted or otherwise secured on the upper edge of the tongue is a micrometer gauge supporting plate 40 which is substantially T-shaped, as shown in Fig. 1. The plate 40 is secured to the upper edge of the tongue 38 by a pair of bolts 42 which are countersunk in the leg portion of the T-shaped plate; the latter portion of the plate is also provided with a central longitudinally extending gouge or concave slot 43 to provide clearance for the barrel of a micrometer gauge M' to be supported on the plate as shown in Fig. 3.

Suitable means for supporting the gauge M' on the plate 40 may, for the purposes of this specification, comprise a yoke consisting of a pair of posts 44 secured at the opposite ends of the head portion of the plate 40 and a link member 45 connecting the spaced posts 44. As shown in Fig. 3, the front end of the micrometer gauge M' which is a standard depth gauge, is adapted to be inserted into the yoke and firmly secured therein by tightening up bolts 46 of the posts 44. Supported in this position, the stem m' of the

gauge is adapted to abut the plate 63 of a second rail or guide means hereinafter described.

From the above description, it will be clear that the frame member 26, rail 36 and micrometer gauge supporting table 40 are secured together as a unit which is normally fixed to the tool holder 16 but which may be readily loosened therefrom and adjusted vertically or laterally with respect to the longitudinal axis of the chuck 30.

A carriage 47 is adapted to slide on the rail 36, and, as shown in Figs. 1, 2, 3 and 7, comprises a pair of spaced parallel plates 48 secured together at one end by a spacer block 49 and bolts 50 and at their opposite ends by one member 53 of a cross-shaped joining or securing means which is shown in Fig. 8 and hereinafter described.

The thickness of each block 49 and 53 is substantially equal to the thickness of the rib 37 and the guide means or tongue 38, whereby the two plates 48 of the carriage will be suitably spaced apart to enable the carriage to slide freely along the rib 37. A suitable relief groove 52, see Fig. 3, may be provided on the inner face of each plate 48 to reduce frictional engagement between the plates and the cooperative faces of the vertical guide or tongue 38.

The cross-shaped securing means or joining member, indicated generally at 54 in Fig. 8, comprises two substantially rectangular plates 53 and 55 of substantially equal thickness and overall dimensions secured together at right angles by a weld joint or other suitable fastening means. The block 53 has a reduced portion 56 at one end adapted to nest in the concave front edge 39 of the tongue 38 when the carriage 47 is moved back on the rail 36 to the position shown in Fig. 3. Both blocks 53 and 55 are provided with a pair of bolt holes 57 and centering pin holes 58. As shown in Fig. 7, suitable bolts 59 of the block 53 are adapted to fixedly secure the latter between the spaced plates 48 of the carriage 47. To this end a transverse slot 480 is provided in the upper edge of each plate 48 of sufficient depth and width to accommodate the transversely extending ends of the block 55 of the cross-shaped joining member 54 and also the members of a second rail or guide means 60 described below which extend transversely of the first rail 36.

This second rail or guide means comprises a pair of spaced parallel plates 63 having relief grooves 64, see Fig. 6, in their inwardly facing surfaces adjacent their respective ends to provide raised bearing surfaces 640; each plate being securely bolted intermediate its end by bolts 62 to the respective faces of the block 55, as shown in Fig. 4. It will be clear, as shown in Fig. 7, that by this construction, the second rail 60 is securely fastened to the carriage 47 at substantially right angles to the longitudinal axis thereof and to the longitudinal axis of the rail 36 on which the carriage is slidably supported. For the purposes of this specification, the unit comprising the carriage 47 and the second rail or guide means 60 secured thereto may be termed a carriage member or carriage unit.

Mounted to slide on the second rail or guide means 60 of the carriage unit is a second carriage 65 comprising a substantially rectangular plate having a pair of vertically depending leg members 66 at its opposite ends, each leg being of suitable thickness to make a snug sliding fit between the bearing surfaces 640 of the second rail 60.

As shown in Fig. 6, suitable relief grooves 67

are formed on opposite sides of each leg opposite the relief grooves 64 of the respective rail plate 63 to provide clearance and to permit the second carriage 65 to slide freely in the second rail member 60.

The portion of the second carriage which extends above the upper edges of the plate members 63 is somewhat thicker than the leg members 66 so as to provide a horizontally extending shoulder 68 along one face of each leg member, each shoulder being adapted to ride on the upper edge 630 of one of the plate members to slidably support the second carriage on the second guide means.

Suitable means are provided for securing the second carriage 65 in the second guide means 60 and comprise apertured disk members 69 fastened by bolts 690 on the lower ends of the leg members 66 and of sufficient diameter to span the lower edges of the plates 63 at each side of the leg members.

For the purpose of lightening the second carriage to facilitate its longitudinal movement on the second rail, suitable apertures 70 may be formed in the plate adjacent its right hand end as viewed in Figs. 1, 2 and 4. In the present embodiment three apertures are shown. At this same end of the second carriage, means are provided for securing a micrometer gauge M^2 to the carriage. The securing means shown comprises a substantially flat longitudinally extending tongue member 72 integral with and in the plane of the plate 65, but somewhat thinner than the latter, as indicated in Fig. 1. A pair of parallel slots 73 are made in the tongue 72, see Fig. 4, to accommodate bolts 74 or other suitable fastening means of a clamp 75, see Fig. 2, which is adapted to embrace the cylindrical portion of the micrometer gauge M^2 to fixedly secure the gauge to the second carriage 65.

Referring to Figs. 1 and 4, the opposite or left hand end of the carriage is shown provided with a U-shaped aperture 76 for accommodating the end of the workpiece or tool T being gauged as the gauging device is advanced longitudinally thereof as hereinafter described. Fixedly secured in the vertical arm 77 formed at the left hand end of the carriage 65 by the aperture 76 is an anvil 78 comprising a substantially rectangular hardened steel block having a square work engaging end 79.

In the present embodiment, the anvil is supported in a horizontally disposed slot 80, milled or otherwise formed in the rear face of the arm 77, the depth of the slot being substantially equal to the thickness of the anvil. Thus, when the anvil is seated in the slot, the exposed surface of the anvil and the rear face of the frame 77 will be substantially flush. A suitable cover plate 82, see Fig. 7, provided with tapped holes is secured by bolts 83 over the slot 80 and serves to hold the anvil immovably therein.

In axial alignment with the fixed anvil 78 is a movable workpiece engaging gauge finger 84 comprising a hardened steel block, the cross sectional dimensions of which are substantially equal to those of the fixed anvil 78 but which is somewhat longer than the latter. The work engaging end 85 of the gauge finger is shown as comprising a substantially square end while the rear end 89 of the block is shaped like a rectangular cone to provide substantially point engagement with the stem m^2 of the micrometer M^2 .

The gauging finger 84 is slidably supported in the right hand end of the carriage 65, as seen in

Fig. 2. To this end, the rear face of the carriage is provided with a substantially rectangular horizontally disposed slot 86 which extends from the edge of the aperture 76 to the extreme right hand end of the carriage 65. The depth and width of the slot 86 are slightly greater than the corresponding dimensions of the gauge finger 84 so that when the finger is seated in the slot, it will be freely slideable therein as indicated in Fig. 5.

5 10 The slot 86 is covered by a cover plate 87 which is provided with tapped holes along its upper and lower edges to receive screw bolts 88 adapted to draw the plate 87 tightly against the rear face of the carriage 65.

15 15 As shown in Figs. 1 and 2, the cylindrical stem m^2 of the second micrometer gauge M^2 is adapted to project into the right hand end of the slot 86 to engage the pointed end 89 of the gauging finger 84.

20 20 To provide clearance for the cylindrical stem m^2 , the slot 86 is provided with an arcuate or semicircular groove 90 in its vertical wall, see Figs. 5 and 6, which extends from the right hand end of the slot to the left substantially three-fourths of its length. A similar arcuate groove 92 is formed in the opposite vertical face of the cover plate 87, the two grooves 90 and 92 cooperating to form a partially cylindrical bore. In accordance with this construction, by rotating 25 30 the micrometer gauge M^2 to advance the stem m^2 , the gauge finger 84 will be advanced in the slot towards the anvil 78.

The gauge units A and B of Fig. 1 are assembled for operation by means of the joining member 54 which, as described above, is fixedly secured between the plates 48 of the carriage 47 and the plates 63 of the rail 60 by suitable bolts 59 and 62, the micrometer gauge M^2 of the second carriage being substantially at right angles to the micrometer gauge M' of the fixed rail 36. The workpiece or tool T to be measured is held fast in the lathe chuck 30 and the assembled gauge 18 fastened to the tool carrier 16 by the clamping means 19 so that the fixed anvil 78 engages one 45 50 side of the tool T. A gauge block 24 of suitable thickness may be inserted beneath the frame 26 to position the longitudinal axis of the gauge finger 84 in the horizontal plane of the longitudinal axis of the tool.

50 55 Measurements of the profile of the workpiece T which, for the purpose of illustration, may comprise the drawing tool, illustrated in Fig. 9, are made as follows. The gauge finger 84 is set initially opposite the end of the tool T by sliding the carriage 47 along the rail 36 either by hand or by manipulation of the micrometer gauge M' and a measurement is made of the diameter of the end of the tool by manipulating the micrometer M^2 to advance the gauge finger 84 into contact with the tool. From this starting position, the carriage 47 will be advanced toward the chuck in equal increments or steps of five hundredths inches by turning the micrometer gauge M' , its stem m' being in engagement with the adjacent plate 63 of the second rail 60. Prior to advancing the carriage 47, however, the operator must first withdraw the stem m^2 of the micrometer gauge M^2 to enable the gauge finger 84 to slide rearwardly in its slot 86. After the carriage 47 has been advanced its first increment or step, the operator manipulates micrometer M^2 to again advance the gauge finger 84 into engagement with the surface of the tool. The reading of the micrometer gauge will be indicative of the diameter of the tool at the first increment or step

along its length. The operator then again retracts the micrometer screw M^2 so as to withdraw the stem m^2 from behind the gauge finger 84 to enable the latter to slide rearwardly freely in its slot and thereafter advances the second rail 60 a second increment at which a second measure of the tool diameter is made by the micrometer gauge M^2 . By performing this same series of operations throughout the entire length of the tool, a series of exact measurements of the profile at equally spaced points therealong will be obtained.

The two micrometer gauges M' and M^2 shown are standard depth micrometers graduated in ten thousandths of an inch, and hence the measurements of the profile are to within ten thousandths inch accuracy.

What is claimed is:

1. A profile measuring device comprising a frame; a micrometer gauge fixedly secured on said frame; a carriage slidably supported on said frame, said carriage having a pair of transversely disposed guide rails; a second carriage mounted to slide freely on said guide rails; and a second micrometer gauge fixedly supported on said second carriage parallel to the longitudinal axis of said guide rails, said first carriage being slidable along said frame by manipulation of said first gauge.

2. A profile measuring device comprising a frame; a micrometer gauge fixedly secured on said frame; a carriage slidably supported on said frame, said carriage having a pair of transversely disposed guide rails; a second carriage mounted to slide freely on said guide rails; a second micrometer gauge fixedly supported on said second carriage parallel to the longitudinal axis of said guide rails, said first carriage being slidable along said frame by manipulation of said first gauge; and rail spinning means on said second carriage for slidably securing said second carriage to said guide rails.

3. A profile measuring device comprising a frame having a substantially vertically depending arm provided with a rail; a carriage unit slidably freely on said rail; a micrometer gauge fixedly secured to said rail parallel to the longitudinal axis of said carriage unit; a second carriage mounted to slide freely on said carriage unit transversely to said rail; and a second micrometer gauge fixedly secured to said second carriage parallel to the longitudinal axis thereof.

4. A profile measuring device comprising a frame having an arm provided with a rail, said rail having an upstanding tongue; a carriage slidable on said rail and constructed and arranged to be guided by said tongue; a micrometer gauge fixedly mounted on said tongue parallel to the longitudinal axis of said carriage, said carriage having a transverse slot; a guide member adapted to fit in said slot; means for securing said guide member to said carriage; a second carriage mounted to slide in said guide member; and a second micrometer gauge supported on said second carriage at substantially right angles to said first micrometer gauge.

5. A profile measuring device comprising a frame having an arm provided with a substantially horizontal rail; a carriage comprising spaced parallel members slidable on said rail, each member having a transverse slot therein; means for supporting said carriage on said rail;

a micrometer gauge fixedly secured to the carriage supporting means substantially parallel to the longitudinal axis of said carriage; a guide member adapted to fit in said transverse slots; means for securing said guide member to said carriage; a second carriage mounted to slide in said guide member; and a second micrometer gauge secured to said second carriage at substantially right angles to said first gauge.

6. A profile measuring device comprising a frame having a substantially vertically depending arm provided with a substantially horizontal rail; a carriage slidable on said rail, said carriage comprising spaced parallel members having transverse slots therein; means integral with said rail and projecting up into the space between the parallel members of said carriage for supporting said carriage on said rail; a micrometer gauge fixedly secured on said supporting means substantially parallel to the longitudinal axis of the rail; a guide member comprising spaced parallel members adapted to fit in said transverse slots; means adapted to fit between the parallel members of said carriage and the parallel members of said guide member to secure said carriage and guide member together; a second carriage adapted to be slidably supported on said guide member transversely to said first carriage; and a second micrometer gauge secured to said second carriage, said first carriage being moved along said rail by engagement of said first micrometer gauge with said guide member.

7. A profile measuring device comprising a frame; a carriage slidable freely on said frame; a guide member comprising spaced parallel rails; means for securing said guide member to said carriage transversely to the longitudinal axis thereof; a second carriage having spaced legs supported to slide freely between the spaced parallel rails of said guide member; rail spanning means for slidably securing said legs between said spaced parallel rails; and a micrometer gauge fixedly secured to said second carriage substantially parallel to the longitudinal axis thereof.

8. A profile measuring device comprising a frame; a carriage slidable freely on said frame; a guide member comprising spaced parallel rails; means for securing said guide member to said carriage transversely to the longitudinal axis thereof; a second carriage slidingly supported between said guide rails, said second carriage comprising a yoke-shaped portion; an anvil secured in one end of said yoke; a gauging bar slidably supported to slide freely in the opposite end of said yoke; and a micrometer gauge secured to said second carriage and adapted to engage said gauging bar to advance said bar toward said anvil.

9. A profile measuring device comprising a frame, a micrometer gauge fixedly secured to the frame; a carriage unit mounted to slide freely on said frame; a carriage mounted to slide freely on said carriage unit at substantially right angles to the longitudinal axis of said micrometer gauge, said carriage having an anvil; and a second micrometer gauge fixedly secured to said carriage and in axial alignment with said anvil and the longitudinal axis of said carriage.

PAUL G. JENNINGS.
